 Mich., jointly

Application January 19, 1942, Serial No. 427,267

6 Claims. (Cl. 296—20)

This invention relates to an army stretcher and more particularly to a mechanism for aiding in the transportation of said stretcher by an attendant at each end thereof. The invention herein resides in an apparatus whereby a large percentage of the weight is borne by a retractable resiliently mounted undercarriage provided with separately mounted wheels for rolling along the ground.

It is the object of this invention to provide an undercarriage for a stretcher or to which a stretcher may be attached whereby as much as 80% of the load is borne by said carriage.

It is a further object of this invention to provide a resiliently mounted undercarriage which may be pivoted into inoperative position when the stretcher is lowered for laying down or removing the patient thus taking very little space, which is equally important for transportation.

It is a still further object of this invention to provide a suitable locking means whereby said undercarriage may be secured in inoperative position.

It is a still further object of this invention to provide for a rolling stretcher of such a light weight that it can easily be lifted by two men when soft ground, or sand or mud makes rolling impossible.

This invention relates to the various arrangements of elements and their combinations as more fully set out hereinafter in connection with the following specification and appended drawings of which:

Fig. 1 is a side elevational view of the stretcher and undercarriage.

Fig. 2 is a partially sectioned front elevational view of the same.

Fig. 3 is a fragmentary elevational view of the resilient undercarriage mounting.

Fig. 4 is a fragmentary side elevational view of the undercarriage locking mechanism in locking position.

Fig. 5 is a front elevational view of the same.

The above drawings are merely by way of illustration, it being intended that various other embodiments of the invention are possible within the scope of the claims hereinafter set out.

Referring to Fig. 1 a stretcher 11 is shown of any conventional type consisting of a pair of parallel bars with a suitable intermediate interconnecting body support made of canvas or other material.

A pair of downwardly depending vertically disposed rests 12 and 13 are provided for engagement at their bottom ends with the ground, while

the upper ends thereof have transversely secured thereto suitable sleeves 14 and 15 adapted for attachment to the stretcher 11.

Rests 12 and 13 as shown in Fig. 2 are suitably inter-connected by a tube 16 or other supporting member thereby providing a rigid body.

Wheels 17 and 18 are rotatably disposed on the end of the two levers 19 and 20 respectively which are adapted to resiliently support said stretcher in the manner more fully set out hereinafter.

Rests 12 and 13, as best seen in Fig. 2, are longitudinally slotted to receive the ends of the cantilevers 21 and 22 which are pivoted respectively to shafts 23 and 24 which are themselves mounted within suitable brackets 25 and 26 secured to the rests 12 and 13.

The upper ends of the levers 19 and 20, which are preferably hollow, are adapted to be connected or joined in any suitable manner to the lower ends of said cantilevers 21 and 22, whereby it is seen that the levers are adapted to pivot independently of each other about the points 23 and 24.

The upper portions of the cantilevers 21 and 22 are pivoted to the bolts 29 and 30 by intermediate pins or shafts 31 and 32. Said bolts have forked ends to receive said cantilever portions 21 and 22.

A transverse opening is disposed through the upper portions of said rests 12 and 13 for reciprocably and slidably journaling the bolt shafts 33 which have on their threaded ends suitable nuts 34 for retaining at the ends of said bolts the washers 35.

A suitable coiled spring 36 is journaled on the bolts 33 and is interposed between the washers 35 and the plate 37.

Thus it is seen that the two levers 19 and 20 which carry the wheels 17 and 18 respectively are pivotally mounted below the stretcher and are joined to the rests 12 and 13. It is further seen that said levers are resiliently mounted to said stretcher and are adapted to rotate counter-clockwise compressing the coiled springs 36.

When the stretcher is brought into rest position by pressure the levers 19 and 20 are pivoted around points 23 and 24 into inoperative position and at the same time wheels 17 and 18 provide a suitable additional rest for the stretcher opposite from the rests 12 and 13 in the manner hereinafter set out.

By virtue of this resilient suspension of the undercarriage it is necessary that said levers be locked in this position to prevent the release of the springs 36 when the patient is lifted from

the stretcher. Suitable latching mechanisms are disposed below the stretcher 11 suitably joined or secured to the depending members 33. Said latching mechanisms 39 are bifurcated and are thereby adapted to receive the respective axles 17' and 18' of the wheels 17 and 18, as best seen in Fig. 4.

Pawl members 40 are pivotally mounted within the lower portion of said latches 39 and are adapted to rotate upwardly permitting said axles 17' and 18' to enter the bifurcated portions in said latches. The pawl closes the latch opening after the axles 17' and 18' have entered the recesses in the bottom portion thereof. Thus it is seen that the axle forces the pawl upwardly and as soon as said axles have cleared said pawl, the same is free to return to the initial position closing off the passage and thereby preventing any downward movement of said axles while the stretcher is in operative loading or unloading position.

In order to release the axles 17' and 18' pawl 40 must be manually elevated thereby opening up said passage; and this is accomplished by a conventional spring type cable 41 joining said pawl member and extending upwardly and along the carriage for manual actuation by one of the stretcher bearers.

It will be noted that each of the wheels 17 and 18 are separately mounted and consequently in traveling over uneven or irregular ground the tilting movements of the said levers are independent of each other.

Having described my invention reference should now be had to the claims which follow in determining the scope thereof.

I claim:

1. The combination with a stretcher of rests joined thereto for supporting one end thereof; and a retractable undercarriage for further supporting said stretcher consisting of levers independently pivoted to said rests, wheels journaled on the ends of said levers, and resilient means remote from said wheels interposed between said rests and said levers adapted to normally urge and maintain said wheels in spaced relation to said stretcher.

2. The combination with a stretcher of rests depending therefrom for supporting one end thereof, and a retractable undercarriage for further supporting said stretcher when in loading position, and to separately support the same when in operative position, consisting of independent levers with cantilevers on the ends thereof disposed through slots in said rests and pivotally joined thereto, wheels journaled on the

other ends of said levers, and resilient means remote from said wheels interposed between said rests and the ends of said cantilevers, adapted to normally urge and maintain said wheels in spaced relation to said stretcher.

3. The combination with a stretcher having a pair of rests for one end thereof; of a retractable undercarriage for further supporting said stretcher, consisting of a pair of independently suspended levers with wheels journaled on the ends thereof, cantilever members joined on the opposite ends thereof slidably disposed through slots in each of said rests, and pivotally joined thereto, bolts slidably disposed through each of said rests with one end thereof pivotally joined to the outer ends of said cantilevers, and resilient means retained on said bolts and interposed between the other ends thereof and said rests respectively.

4. The combination with a stretcher of rests joined thereto for supporting one end thereof; and a retractable undercarriage for further supporting said stretcher consisting of levers independently pivoted to said rests, wheels journaled on the ends of said levers, resilient means remote from said wheels interposed between said rests and said levers adapted to normally urge and maintain said wheels in spaced relation to said stretcher, and adjustable means on said bolts for regulating the tension of said resilient means.

5. The combination with a stretcher of rests joined thereto for supporting one end thereof; and a retractable undercarriage for further supporting said stretcher consisting of levers independently pivoted to said rests, wheels journaled on the ends of said levers, resilient means remote from said wheels interposed between said rests and said levers adapted to normally urge and maintain said wheels in spaced relation to said stretcher, and means in said rests adapted to limit the outward movement of said resiliently mounted levers.

6. The combination with a stretcher of rests joined thereto for supporting one end thereof; and a retractable under-carriage for further supporting said stretcher consisting of levers independently pivoted to said rests, wheels journaled on the ends of said levers, resilient means remote from said wheels interposed between said rests and said levers adapted to normally urge and maintain said wheels in spaced relation to said stretcher, and latching means depending therefrom engageable with said retractable under carriage for securing said wheels in retracted position.

ERNEST FRIEDLAENDER.
